EXCAVATING SHOVEL

Walter Baker, Cedar Rapids, Iowa, assignor, by
mesne assignments, to Link-Belt Speeder Cor-
poration, a corporation of Illinois

Application June 4, 1937, Serial No. 146,471

11 Claims. (Cl. 214—135)

This invention relates to excavating shovels and has particular relation to means for rotating the turn table and running gear of such shovels.

In excavating machinery of the character here considered the shovel is usually mounted on wheels or endless track for moving the shovel about during operation thereof. The driving mechanism for driving the endless track is so geared down as to furnish tremendous power for rotating the track and, of course, under these conditions the track speed is not high. Consequently, if it is necessary to move the shovel from one job to another the track speed is so low that it takes too long to transport the shovel under its own power and heavy trucks must be employed for the purpose. Of course, higher gearing may be employed but obviously this would not furnish sufficient power to the track when the shovel was in use.

While multiple-speed mechanisms have been proposed for excavating shovels such devices have employed either multiple speeds at the prime mover resulting in multiple speeds of all operations or have been confined to the mounting of complex gear arrangements under the turn table or in the lower deck where they are inaccessible and subject to excessive wear and clogging due to being close to the ground and obstacles such as stones and the like, lessening ground clearance.

It is accordingly an object of my invention to provide a plural speed drive for excavating shovels and the like.

It is a more specific object of my invention to provide a plural speed drive for excavating shovels which may be incorporated in the usual shovel structure without material change thereof.

It is an object of my invention to provide a simple and accessible multiple speed mechanism with a minimum number of working parts.

It is another object of my invention to provide a new and improved excavating shovel and a new and improved means for moving the shovel from one job to another.

Other and further features and objects of the invention will be more apparent to those skilled in the art upon a consideration of the accompanying drawings and following specifications, wherein is disclosed a single exemplary embodiment of the invention, with the understanding, however, that such changes may be made therein as fall within the scope of the appended claims, without departing from the spirit of the invention.

In said drawings:

Figure 1 is a view in perspective of the left side of an excavating shovel constructed according to my invention.

Figure 2 is a view in perspective of the right side of the shovel shown in Figure 1.

Figure 3 is a view in perspective of the engine, hoisting drums, and operating mechanism of the device shown in Figures 1 and 2.

Figure 4 is a plan view in diagrammatic relation of the drive of a shovel constructed according to my invention.

Figure 5 is a view in elevation in diagrammatic relation of the drive mechanism shown in Figures 1 to 4 inclusive.

Figure 6 is a view from beneath the shovel illustrating the running gear and running gear drive.

Figure 7 is a view in section of the track drive gearing with the double jawed clutch in engagement with the high speed gears, and

Figure 8 is a view in section of a portion of the drive shown in Figure 7 with the clutch in engagement with the slow speed gears.

A shovel constructed according to my invention has an upper revolving frame 10 on which a boom 11 is pivotally mounted. The A-frame legs 12 and 13 are adapted to support the boom by means of boom hoist cables 14. The dipper stick 16 is mounted for in and out movement on dipper stick roller 17 and is either thrust downwardly by means of a crowding drum 18 or retracted by means of cable 19 which is operated by reversing the crowding drum 18, the reverse being accomplished by means of the chain drive indicated at 21. The shovel 22, of the usual type, is adapted to be swung for digging by means of the cables and sheaves indicated generally at 23 and these are actuated by means of the hoisting drum 24. The door 26 of the shovel 22 may be opened or tripped by means of the trip rope 27 which may be pulled by the operator by hand.

Power for operating the various sheaves and driving the excavating shovel is furnished by means of any prime mover such as the gasoline engine indicated at 31. The upper revolving frame is mounted for rotation on the turntable 32 and is preferably mounted on the turntable by means of rollers 33 which permit the turntable to rotate in accordance with the usual turntable drive hereinafter discussed. The turntable 32 is mounted on a lower frame 34 and this frame in turn is mounted upon running gears or tread members indicated generally at 36.

55 A tread drive sprocket 37 at one end of each

of the tread frames 36, and tread rollers 38 at the other end of the tread frames 36, afford means by which the endless tracks 39 may be rotatably mounted. The springs 41 serve as take-ups for the idler wheels 38 and also serve to relieve stress on the idler sprockets in the event that any stones or the like get into the track. The portions of the tracks 39 which are in contact with the ground are held in relatively flat position by means of a plurality of rollers 43.

Returning now to the drive gearing, and referring more particularly to Figures 4 and 5, the prime mover 31 is adapted to drive a large sprocket wheel 46 by means of a chain 47 or other suitable drive means. The sprocket wheel 46 is mounted on the main power shaft 48. The main power shaft 48 is adapted to drive a reverse shaft 49 by means of a pinion 51 on shaft 48 and a gear 52 which is mounted on the reverse shaft 49. The gear 52 in turn drives a front drum gear 53 and a rear drum gear 54, the front drum gear being mounted on a front drum shaft 56 and the hoisting drum gear 54 being mounted upon a hoisting shaft 57. The crowding drum or front drum 18 is keyed to the shaft 56 but the shaft may be engaged or disengaged at will to the gear 53 by means of a clutch indicated at 63. The shaft 56 may also be engaged or disengaged to a reversing clutch indicated at 64 to reverse the direction of rotation of the drum 18, the drive for reversing the drum being afforded by means of a sprocket chain 66 and a sprocket gear 67 on clutch 64 and another sprocket gear 68 on the shaft 49. The hoisting drum 24 may be engaged to the hoisting drum gear 54 by means of a clutch indicated at 73. Reverse action of the drum, of course, is afforded by means of the weight of the boom.

A boom hoist drum 72 is provided for winding the boom hoisting cables 14 and this drum is adapted to be driven by means of a sprocket 74 which may be engaged or disengaged to the shaft 49 by means of clutch 76. The sprocket 74 drives a chain 77 which in turn drives a sprocket 78 and this sprocket is mounted on a shaft 79. The shaft 79 rotates a pinion 81 which in turn drives a gear 82 to rotate the boom hoist drum 72.

The track 39 is adapted to be rotated by means of the shafting and gearing which I am about to describe. The reverse gear shaft 49 has a pair of clutches 86 and 87 and these are adapted to rotate a forward drive bevel gear 88 and a reverse bevel gear 89. These bevel gears rest on and drive horizontally disposed bevel gear 91 and this gear is pinned to the vertical drive shaft 92. Normally the shaft 92 is engaged to a drive gear 93 which in turn drives a second gear 94 and a third traction drive gear 96, but coupling of the drive pinion 93 with the shaft 92 is afforded by means of a clutch 97, the jaws of which will either engage the low speed drive pinion 93 (Fig. 8) or a high speed drive pinion 98 (Fig. 7). The high speed drive pinion 98 in turn engages a high speed gear 99 and this gear 99 is fastened directly to the gear 94.

In the high speed position of the clutch 97, the gear 93 is disengaged by the clutch and the gear 98 is engaged in order to furnish a high speed of rotation to the traction gear 96. The shaft 101, called the swing shaft, is provided with a pinion 102 at the lower end thereof adapted to engage the internal teeth of the turntable gear 103 for rotating the upper revolving frame on the turntable 32. Obviously, the turntable 75

may be rotated in one direction or the other as desired by engaging and disengaging the clutches 86 and 87. The shaft 101 may be coupled to the gear 99 by means of the jaw clutch 104 for rotating the upper platform.

Traction clutch 106 is provided which is splined to the traction drive shaft 107 and in its engaged position engages the gear 96 to the shaft 107 to drive the crawler tracks, this drive being provided by means of a bevel gear 108 on the lower end of the shaft 107 which engages the bevel gear 109. The bevel gear 109 is keyed to a shaft 111 and this shaft in turn drives chain sprockets 112 and 113 located on the opposite ends of shaft 109. The chain sprockets 112 and 113 are adapted to be driven by means of jaw clutches 114 and 116 and either of the chain sprockets 112 or 113 or both may be driven by engaging the clutches 114 or 116. The members 117 are stationary 20 brakes for preventing rotation of the respective shafts. The chain sprockets 112 and 113 drive chains 118 and 119 which in turn drive the large sprockets 37.

The train of gears 93, 94 and 96 will provide a low speed, suitable while the shovel is in use in excavating and where considerable power is required but low speeds are all that are necessary. In transporting the shovel from one job to another, it is desirable that a high speed be provided and this high speed is provided by means of the high speed gears 98 and 99. In using the high speed gearing the jaw clutch 97 is raised to disengage the gear 93 and engage the gear 98.

If the jaw clutch 104 is engaged to the gear 99 and the clutch 97 engaged to gear 98, the upper revolving frame will revolve at high speed. If the clutch 104 is engaged to gear 99 and the clutch 97 engaged to the gear 93 the table will rotate at low speed. If the clutch 104 is disengaged and the clutch 106 engaged and the jaw clutch 97 is raised to its upper position, the high speed gearing 98 and 99 is engaged to drive the tracks at high speed to move the shovel rapidly from one job to another. If the clutch 106 is engaged, the clutch 104 disengaged and clutch 97 engaged to gear 93, the tracks will be driven at low speed with corresponding increase in power. Engagement and disengagement of the double jaw clutch 97 is accomplished by the operator through manipulation of the lever 121 which is operatively engaged to the clutch. The machine is controlled by the group of levers indicated generally at 122 in accordance with the usual practice.

Obviously, my invention may be applied to wheel type cranes and shovels, whether railway cranes, road type wheels, flanged rail wheels or various types of traction locomotion.

It is apparent that modifications may be made by those skilled in the art. Such modifications may be made without departing from the spirit and scope of my invention as set forth in the appended claims.

I claim as my invention:

- In an excavating shovel mounted on running gears having endless tracks, a turntable, a prime mover on the turntable, winding drums driven by the prime mover, a vertical shaft passing downward through the axis of the turntable, means for connecting this shaft with the wheels of the running gear, a pair of gear trains for driving the vertical shaft from the prime mover, and selective means for engaging one or the other of the gear trains, said gear trains including a pair of gears mounted for rotation

on a swing shaft and a means for selectively engaging the gears to the shaft.

2. In an excavating shovel, running gear, a lower frame, an upper revolving frame, a prime mover mounted on the revolving frame, means for driving the running gear from the prime mover including a drive shaft in the revolving frame, a vertical drive shaft driven from the first named drive shaft, a pair of gears mounted for rotation on the vertical drive shaft, a pair of idler gears with which the first named gears engage mounted for free rotation on a swing shaft, clutch means on the vertical drive shaft for engaging one or the other of the first named gears, clutch means on the swing shaft to engage the idler gears with the swing shaft, a traction shaft, a gear rotatably mounted thereon engaging with one of the idler gears, and clutch means to engage the traction shaft with the last mentioned gear.

3. In an excavating shovel, a lower frame, track rotatably mounted on the lower frame, means for driving the track, an upper frame rotatably mounted on the lower frame, a drive shaft for driving the track passing down through the axis of rotation of the upper frame, a driven gear mounted for rotation on this vertical drive shaft, a clutch means for engaging the driven gear to the drive shaft, an idler shaft, a pair of gears on the idler shaft, one of which engages the first named gear, a drive shaft and a pair of gears on the drive shaft meshed with the first named pair of gears, and clutch means for engaging one or the other of the last named gears, and a prime mover operatively engaged for driving the drive shaft, the idler shaft adapted to be engaged with the pair of gears mounted thereon and cause the rotation of the upper frame with respect to the lower frame.

4. In an excavating shovel, a lower frame, running gears on the lower frame, tracks on the running gears, and drive means for driving the track, a turntable rotatably mounted on the lower frame, a prime mover on the upper frame, a power shaft, means for driving the power shaft from the prime mover, a hoisting drum and crowd drum driven by the drive shaft, a reverse gear drive shaft driven from the main power shaft, bevel gearing, forward and reverse, driven by the reverse gear drive shaft, a first vertical shaft driven by the bevel gearing, a first gear train driven from said vertical shaft, a second vertical drive shaft passing downwardly through the center axis of the turntable, bevel gearing and a second train of drive gearing for driving the tracks from said second vertical shaft, said second vertical shaft being driven by the first named train of gears, and an alternative train of gears between the first named vertical shaft and second named vertical shaft for furnishing two speed drive to the tracks.

5. In an excavating shovel, a running gear, a turntable pivotally mounted on the running gear, a prime mover on the turntable, a vertical drive shaft driven by the prime mover, a swing shaft, drive gears on the drive shaft, idler gears rotatably mounted on the swing shaft and engaging the drive gears, clutch means on the drive shaft for selectively driving one or the other of the drive gears mounted thereon, clutch means on the swing shaft for selectively driving the swing shaft through one of the idler gears on the swing shaft, a traction drive shaft, a traction drive gear mounted on the traction

shaft engaging one of the idler gears, and clutch means on the traction drive shaft for selectively engaging and disengaging the drive gear.

6. In an excavating shovel, a vertical drive shaft, a pair of drive gears journalled on the drive shaft, clutch means for selectively engaging the drive gears to the drive shaft, a swing shaft, a pair of idler gears journalled on the swing shaft and meshing with the drive gears, clutch means for selectively engaging or disengaging the swing shaft, a traction drive shaft meshing with one of the idler gears on the swing shaft, and clutch means for engaging and disengaging the traction drive shaft to the traction drive gear, said construction adapted to permit a change of speed of either the traction drive shaft or the swing shaft by the operation of one clutch means.

7. In an excavating shovel, a drive shaft and plural drive gearing means journalled on this drive shaft, a swing shaft and plural gearing journalled on the swing shaft meshing with the plural gearing on the drive shaft, a traction drive shaft and a traction drive gear meshing with one of the gears on the swing shaft, clutch means on the first drive shaft for selectively driving the plural gearing, clutch means on the swing shaft for engaging and disengaging the swing shaft to the gearing on the swing shaft, and clutch means on the traction drive shaft for engaging with and disengaging from the traction drive shaft the gear journalled on the traction drive shaft.

8. In an excavating shovel, a lower frame, running gear on the frame, an upper frame pivotally mounted on the lower frame, a power means on the upper frame, a jack shaft, a vertical drive shaft, opposed bevel gears of equal size on the jack shaft, a bevel gear on the drive shaft adapted to be selectively engaged with one of the opposed bevel gears to selectively rotate the drive shaft in one direction or the other, a swing shaft, a plurality of drive gears on the drive shaft, a plurality of idler gears adapted to rotate as one rotatably mounted on the swing shaft and engaging the drive gears, clutch means on the drive shaft to selectively drive one of the drive gears to change speed, clutch means on the swing shaft for selectively driving the swing shaft through one of the idler gears, a traction drive shaft engaging one of the idler gears, and clutch means on the traction drive shaft.

9. In an excavating device, a lower frame, endless tracks mounted thereon, an upper frame mounted for rotation on the lower frame, a power means on the upper frame, winding drums adapted to be driven therefrom, a jackshaft, a drive shaft driven from the jackshaft, a plurality of drive gears rotatably and independently mounted on this shaft, clutch means for selectively engaging the drive shaft to any one of the said drive gears, a swing shaft, a plurality of swing shaft gears mounted for rotation on the swing shaft but secured to one another and meshing with their respective drive gears, a clutch for connecting the swing shaft to the swing shaft gears, a traction drive shaft, a traction drive shaft gear meshing with one of the swing shaft gears, and a clutch for engaging the traction drive shaft with the traction drive shaft gear for selectively engaging and disengaging the drive gear.

10. In an excavating device, including a platform, endless tracks on the platform for transporting the same, a turntable rotatably mounted on the platform and a power source on the turn-

table, driving means on the turntable including drums for actuating the excavating device, and a two-speed drive means for rotating the turntable and for driving the endless tracks, said two-speed drive means including a double train of gears, a power take off drive shaft driven by the power source, and a two way clutch on the power take off drive shaft to engage the first gear of one or the other of the train of gears, a single jawed clutch and swing shaft take off for selectively engaging intermediate gears in the double gear train for rotating the turntable, and another single jawed clutch and traction take off shaft engaging the last gear of the gear train for driving the endless tracks, the speed change for both the swing shaft and traction shaft being effected by means of the two way clutch on the power take off drive shaft.

11. In an excavating device including a platform, endless tracks for transporting the platform, and a turntable on which the excavating device is mounted, a power means on the turntable, drums driven from the power means, a power take off from the power means for rotating the turntable and driving the tracks, the power take off including two gears of different pitch diameter, and a two way clutch for selectively engaging one or the other of the gears, two driven gears driven from the first named gears, a swing drive shaft for rotating the turntable, a clutch for engaging this swing drive shaft to the last named gears, a fifth gear and a traction drive shaft for driving the endless tracks, and a clutch means for engaging and disengaging the traction drive shaft with the fifth gear.

WALTER BAKER.
